UNITED STATES PATENT OFFICE.

WILLIAM F. CREMEAN, OF LOGAN, OHIO.

GRINDING-MACHINE.

1,026,022.

Specification of Letters Patent.

Patented May 14, 1912.

Application filed November 1, 1911. Serial No. 657,953.

To all whom it may concern:

Be it known that I, WILLIAM F. CREMEAN, a citizen of the United States, residing at Logan, in the county of Hocking and State 5 of Ohio, have invented certain new and useful Improvements in Grinding-Machines, of which the following is a specification.

My invention relates to improvements in that class of portable grinders which may 10 be fixed to the shaft or member which is to be ground, or to adjoining portions of the structure of which it is a part.

The object of my improvements is to provide a new and useful portable grinding 15 machine which may be easily transported and quickly mounted upon the part to be ground without other support than the part to be ground or the adjacent structure of which it is a member.

20 I attain this object by the mechanism illustrated in the accompanying drawings in which—

Figure 1 is a longitudinal section through the machine mounted upon a car axle, for 25 grinding the journal. Fig. 2 is an end view of the machine shown in Fig. 1. Fig. 3 is a section on line *a a* of Fig. 2. Fig. 4 is a section on line *b b* of Fig. 2. Fig. 5 is a section on line *c c* of Fig. 2. Fig. 6 is a 30 section on line *d d* of Fig. 2. Fig. 7 shows a modification of my machine for mounting upon a shaft at a distance from its end, and shows further an arrangement for motor drive. Fig. 8 shows a detail of 35 the clamping device for the stationary frame shown in Fig. 6. Fig. 9 is an end view of ring 7.

In Figs. 1 and 2 the machine is shown 40 fixed to a car axle and wheel for the purpose of grinding the axle journal which may have become worn or roughened in service or have been left unfinished by the lathe in which it was turned. The machine is equally adapted to be attached to other 45 forms of shafts or cylindrical machine parts, as is shown in Fig. 7.

Advantages of this machine are that its 50 use obviates the necessity of sending a rough axle or shaft to a machine shop to be trued up, and saves in both expense and time in the repairing of axles or other cylindrical parts which have become unfit for service. Further advantages lie in the ease with 55 which the machine may be transported, and mounted upon large or unwieldy shafts or machine parts which would otherwise have

to be handled and ground by large and expensive grinding apparatus.

In the drawings 1 represents a car axle, and 2 is a car wheel mounted upon it.

60 3 and 4 are gears which are securely fastened together in alinement and fixed relative position by the shouldered rivets 5—5, forming a revoluble frame.

65 6—6 are wedges which occupy slots in the externally threaded ring 7 for the purpose of clamping the axle or member to be ground and for alining the gear 3 relative to it.

70 8 is an internally threaded ring which screws over the ring 7, and drives the wedges 6—6 evenly into their slots in it and against the axle. The outer surface of the ring 8 forms a bearing on which revolves gear 3. Ring 8 has an outwardly projecting 75 flange 9 which forms a retaining shoulder for the gear 3, and an inwardly projecting flange 10 which presses the wedges 6—6 into place. Ring 7 has an outwardly projecting flange 11 which forms the other retaining shoulder for gear 3. Both rings 7 and 8 are bored somewhat larger than the nominal diameter of the axle upon which they are mounted, to accommodate slight variations in size, the use of the wedges 6—6 85 permitting such an arrangement.

80 On the outer end of the journal which is to be trued is placed the sleeve 12 which is provided with a trunnion-like extension 13. The outer surface of the sleeve 12 forms a 90 bearing on which revolves the gear 4. A retaining flange 14 projects from sleeve 12. Projecting axially through and closely centered with the trunnion 13 of sleeve 12 is a 95 pin 15, formed at one end into a lathe center for the purpose of entering the countersunk hole in the center of the end of the axle.

100 16 is a tripod-like stationary frame provided with inwardly projecting feet 17, and cam clamps 18. In the leg 19, of tripod 16 are the bearings 20—21 for drive shaft 22. Keyed to drive shaft 22 are pinions 23—24 and large gear 25 which as shown is utilized as a crank disk for hand crank 26, when hand power is applied to drive the machine. 105 When assembled for operation, pinions 23—24 mesh with and drive gears 3—4. The leg 19 of the tripod 16 is forked at the bearing 21 and joins the other two legs 27—28, on either side of the center in such a 110 way as to clear gear 25 and other parts of the mechanism. The legs 27—28 of the tri-

pod join in a hub at 29 which is threaded internally for the centering pin 15.

30 is a retaining washer for gear 4.

Upon the trunnion 13 of sleeve 12 runs 5 freely the wide faced intermediate gear 31, driven by gear 25. Gear 31 drives gear 32, through the idler gear 33. Gear 32 is keyed to the driven shaft 34 which carries the abrasive wheel 35 and drives it by means 10 of a sliding key 36 in spline 37.

To permit lateral adjustment of wheel 35, relative to the member which is to be ground, there are provided bearing brackets 38-39 for the shaft 34. These brackets are keyed 15 to a shaft 40, which, passing through from outside to outside of gears 3-4, is co-axial with gear 33, and is pivoted with the brackets 38-39 in bearings in the webs or spokes of gears 3-4. Gear 33 runs freely upon 20 the trunnion extension 41 of bracket 38, and is held in place by the screw 42 and washer 43. The brackets 38-39 when adjusted so that wheel 35 grinds the diameter desired are secured in position by the clamping bolt 25 44 and nut 45. Tube 44^a is a spacer for gears 3 and 4 to resist the clamping force of the bolt 44. To permit such adjustment the webs or spokes of gears 3-4, which form the end walls of the revoluble frame are 30 slotted at 46-47-48-49. The abrasive wheel 35, being mounted upon the shaft 34 which has its bearings in the revoluble frame is made to rotate about the part being ground by the pinions 23-24 driving the 35 gears 3-4.

For the purpose of causing the abrasive wheel to travel longitudinally along the part to be ground, I provide a feeding mechanism as follows.—Extending longitudinally 40 through gears 3-4 and having bearings in the spokes or webs thereof is a shaft 50. This shaft is threaded throughout its portion which lies between the gears 3-4 and carries upon it a nut 51, which has laterally extending arms 52-53, which span the wheel 35. Keyed to shaft 50 is a star wheel 54, which is made to rotate in either direction, according to whether striking pin 55 is placed in hole 56 or 57 in the tripod leg 50. The rotation of shaft 50 propels nut 51 upon it and the arms 52-53 feed the abrasive wheel 35 axially parallel to the member being ground. Gears 3 and 4 are recessed at 3^a and 4^a to permit the wheel 35 55 to have full travel.

In Fig. 7 there is shown an arrangement for connecting the machine to a motor by means of belt pulley 58 mounted upon shaft 22. In this figure the machine is shown 60 mounted upon a shaft at a distance from the end. For this adaptation of my invention, the centering pin 15 and sleeve 12 of Fig. 1 are not used but there are employed for mounting gear 4, sleeves 8^a, 12^a, and wedges 6^a-6^a which are used in the same

manner relative to gear 4, as the corresponding parts 6-7 and 8 are used for gear 3. In this adaptation, also, the tripod frame 16 which in Fig. 1 is clamped to a car wheel, is modified to permit of its being clamped 70 to the projecting portions of the shaft being ground. This modification is shown in Figs. 7 and 8 by the legs 16^a 16^a which are clamped to the shaft to be ground, 1^a by the bar 59, 59^a and the bolts 60-61, etc.

Other modifications of my invention may be made to adapt it to the specific work to be performed without material modification of its functions or the means employed to perform them, as will be apparent to those 80 skilled in the art.

To attach and operate my machine, as shown in Figs. 1 and 2, the ring 7 is first slipped over the journal to be ground and the wedges 6-6 which may be three or more 85 in number are slipped into their slots. Gear 3 is next slipped over the end of the journal followed by ring 8. Gear 4 follows with sleeve 12, washer 30, and wide faced gear 31. Gear 3 is now slipped upon its bearing on 90 ring 8 and the latter screwed on to ring 7, at the same time tightening the wedges 6-6. Sleeve 12 which carries gear 4 follows by sliding on to the end of the journal. The stationary tripod frame carrying the driving gears 23-24-25 is now dropped into 95 place and the centering pin 15, having a threaded portion connecting it to the hub of the tripod frame, is inserted into the countersunk hole in the end of the axle. 100 The gearing being brought to proper adjustment, the stationary frame 16 is clamped to the wheel by means of the clamps 18-18-18. The adjustment of the stationary frame is facilitated by means of set screws 105 such as 62-63-64-65. The bearings for the shaft of the abrasive wheel 35 are now adjusted so that the wheel will grind the proper amount, the star wheel striker set so as to feed the wheel 35 in the proper 110 direction and the operation of grinding performed by rotating the gear 25. To reverse the longitudinal feed of the grinding wheel the striker pin 55 is removed from one of the holes 56 or 57 and placed in the other. 115

The attachment and operation of my invention as shown in modified form in Figs. 7 and 8, are clearly shown in the drawings.

What I claim and desire to secure by Letters Patent is—

1. In a grinding machine the combination of a revoluble frame, a shaft having bearings therein and bodily revoluble therewith, an abrasive wheel carried by the shaft, means for rotating said wheel on its axis while 125 bodily rotating with the frame, and a feeding mechanism for the abrasive wheel mounted in the revoluble frame.

2. In a grinding machine the combination of a revoluble frame, a shaft having bear- 130

ings therein, an abrasive wheel carried by the shaft, a feeding mechanism for the abrasive wheel mounted in the revoluble frame, means for rotating the revoluble frame, 5 means for rotating the abrasive wheel on its axis while bodily rotating with the revoluble frame, and means for operating the feeding mechanism.

3. In a grinding machine the combination 10 of a revoluble frame, a shaft having bearings therein, an abrasive wheel carried by the shaft, means for rotating the abrasive wheel, while bodily revolving with said frame, a feeding mechanism for the abrasive wheel mounted in the revoluble frame, bearings for the revoluble frame and means for mounting them upon the shaft to be ground.

4. In a grinding machine the combination 20 of a revoluble frame, a shaft having bearings therein, an abrasive wheel carried by the shaft, feeding mechanism for the abrasive wheel mounted in the revoluble frame, bearings for the revoluble frame, means for 25 mounting said bearings upon the shaft to be ground, means for rotating the revoluble frame, means for rotating the abrasive wheel on its own axis while bodily rotating with said frame, and means for operating 30 the feeding mechanism.

5. In a grinding machine, the combination 35 of a revoluble frame, a shaft having bearings therein, an abrasive wheel carried by the shaft, a feeding mechanism for the abrasive wheel mounted in the revoluble frame, bearings for the revoluble frame, means for mounting said bearings upon the shaft to be ground, a stationary frame, a drive shaft having bearings therein, and separate driv- 40 ing connections between the drive shaft and the revoluble frame and between the drive shaft and the shaft carrying the abrasive wheel whereby the abrasive wheel will be rotated on its own axis and bodily fed side- 45 wise while bodily rotating about the shaft being ground.

6. In a grinding machine, the combination 50 of a revoluble frame, a shaft having bearings therein, an abrasive wheel carried by the shaft, feeding mechanism for the abrasive wheel mounted in the revoluble frame, bearings for the revoluble frame, means for mounting them upon the shaft to be ground, a stationary frame, independent means for 55 mounting it upon the shaft to be ground, a drive shaft having bearings in the stationary frame, and separate driving connections between the drive shaft and the revoluble frame and between the drive shaft and the 60 shaft carrying the abrasive wheel, whereby the abrasive wheel will be rotated on its own axis and bodily fed sidewise while bodily rotating about the shaft being ground.

7. In a grinding machine the combination 65 of a revoluble frame and a stationary frame,

the revoluble frame being carried by two separated bearings secured to and alined with the shaft to be ground, said revolving frame embodying two large gear wheels journaled respectively on said bearings. 70

8. In a grinding machine, the combination of a revoluble frame and a stationary frame, the revoluble frame being carried by two separated bearings secured directly to and alined with the shaft to be ground and the stationary frame being independently secured to the shaft to be ground or the structure of which it is a member. 75

9. In a grinding machine, the combination 80 of a revoluble frame and a stationary frame, the revoluble frame carrying the bearings for the shaft of the abrasive wheel and its feeding mechanism, and being revoluble upon bearings co-axially mounted directly upon the shaft to be ground at opposite ends 85 of the surface to be ground.

10. In a grinding machine the combination 90 of a revoluble frame and a stationary frame, the revoluble frame carrying the bearings for the shaft of the abrasive wheel and its feeding mechanism and being revoluble upon separated bearings co-axially mounted directly upon the shaft to be ground at opposite ends of the surface to be ground, the stationary frame carrying the 95 bearings for the drive shaft for the revoluble frame and the abrasive wheel and being secured to the shaft to be ground or the structure of which it is a member.

11. In a grinding machine the combination 100 of a revoluble frame, a shaft having bearings therein, an abrasive wheel carried by the shaft, a feeding mechanism for the abrasive wheel mounted in the revoluble frame, a stationary frame, a drive shaft having bearings therein and means independent 105 of the stationary frame for mounting the revoluble frame co-axially and directly and wholly upon the shaft to be ground.

12. In a grinding machine the combination 110 of a revoluble frame and a stationary frame and independent means for mounting them upon the shaft to be ground, the revoluble frame embodying a pair of large gear wheels journaled in bearings mounted directly on the shaft to be ground. 115

13. In a grinding machine the combination 120 of a stationary frame carrying the driving members, a revoluble frame carrying the driven members, means for mounting the revoluble frame directly upon the shaft to be ground, and independent means for securing the stationary frame to the shaft to be ground or the structure of which it is a member. 125

14. In a machine for grinding shafts, the combination of a stationary frame, a drive shaft journaled therein and carrying a pair of pinions and a large gear wheel, with a revoluble frame embodying a pair 130

of large gear wheels journaled on bearings directly mounted on the shaft to be ground, these wheels being in mesh with the aforesaid pinions, a shaft journaled in the revoluble frame and carrying an abrasive wheel, means operated from the aforesaid large driving gear for rotating said wheel while bodily rotating, and means for automatically feeding said wheel laterally during its 10 planetary movement.

15. In a grinding machine, a revoluble frame, a shaft having bearings therein parallel to the axis of the revoluble frame, the shaft being splined for a portion of its 15 length, an abrasive wheel mounted upon the shaft and rotated by a key in the spline but free to move longitudinally, means for feeding the abrasive wheel longitudinally, means for revolving it upon its axis and 20 means for causing the abrasive wheel to rotate about the shaft being ground.

16. In a grinding machine, an abrasive wheel, a shaft therefor, a revoluble frame, adjustable bearings for said shaft in said 25 frame, bearings for the revoluble frame, means for mounting said bearings co-axially upon the shaft to be ground, separate means for rotating the abrasive wheel upon its axis, for revolving it about the shaft 30 being ground and for feeding it longitudinally.

17. In a grinding machine, an abrasive wheel, a splined shaft therefor, sliding key connections between the shaft and the hub 35 of the abrasive wheel, a revoluble frame consisting of a pair of gears held in axial alinement, and bearings for said shaft carried by said revoluble frame.

18. In a grinding machine the combination 40 of an abrasive wheel, a splined shaft therefor, sliding key connections between the shaft and the hub of the abrasive wheel, a gear keyed to said shaft, a revoluble frame consisting of a pair of gears held in 45 axial alinement, bearings for the splined shaft carried by the revoluble frame, a feeding mechanism for the abrasive wheel carried by the revoluble frame, bearings for the revoluble frame adapted to be

50 mounted upon the shaft to be ground in co-axial alinement therewith, a stationary frame, a drive shaft having bearings therein, a gear keyed to the drive shaft and adapted to mesh with a gear of the revoluble frame, a second gear keyed to the drive 55 shaft, driving connections between said second gear and the gear keyed to the splined shaft, means for supporting the stationary frame in alinement with the revoluble frame, means for operating the feeding 60 mechanism, and means for imparting motion to the drive shaft.

19. In a machine for grinding shafts, a stationarily mounted frame, an independent frame journaled on bearings directly mounted 65 on the shaft to be ground, said bearings being located at opposite ends of the surface to be ground, a rotatable shaft journaled in said rotatable frame and carrying a laterally movable abrasive wheel, mechanism mounted on said stationary frame for simultaneously revolving the rotatable frame and the shaft carrying the abrasive wheel, and means for automatically shifting the abrasive wheel laterally on its shaft 70 during its planetary movement.

20. In a grinding machine, the combination of an abrasive wheel, a stationary frame carrying a driving member, a revoluble frame carrying driven members, means for 80 mounting the revoluble frame upon the shaft to be ground in alinement therewith, separate means for securing the stationary frame to the shaft to be ground or the structure of which it is a member in alinement 85 with the shaft to be ground, means for imparting motion to the driving member, driving connections between the driving and driven members, means for feeding the abrasive wheel longitudinally, and means 90 for varying its lateral position relative to the shaft being ground.

In testimony whereof I have affixed my signature in presence of two witnesses.

WILLIAM F. CREMEAN.
